US00D591232S

(12) **United States Design Patent**
Zhuang

(10) **Patent No.:** **US D591,232 S**
(45) **Date of Patent:** **** Apr. 28, 2009**

(54) **BATTERY POWER PACK**

(76) Inventor: **York Zhuang**, A2 Building, Dahe Industrial Area, Huanguan South Road, Guan Lan, Shenzhen (CN) 518110

(**) Term: **14 Years**

(21) Appl. No.: **29/308,518**

(22) Filed: **Jun. 23, 2008**

(51) **LOC (9) Cl.** 13-02

(52) **U.S. Cl.** D13/103

(58) **Field of Classification Search** D13/102–106, D13/110, 118–121, 184; 429/96–100, 163, 429/176

See application file for complete search history.

(57) **CLAIM**

I claim the ornamental design for a battery power pack, as shown and described.

DESCRIPTION

FIG. 1 is a front perspective view of the battery power pack design;

FIG. 2 is a rear perspective view of the of the battery power pack design;

FIG. 3 is a front elevational view of the battery power pack design;

FIG. 4 is a side elevational view of the battery power pack design;

FIG. 5 is a side elevational view of the opposed side of the battery power pack design;

FIG. 6 is a rear elevational view of the battery power pack design;

FIG. 7 is a top view of the battery power pack design; and,

FIG. 8 is a bottom view of the battery power pack design.

1 Claim, 7 Drawing Sheets
